UNITED STATES PATENT OFFICE.

JO. RAMSEY, OF MILFORD, TEXAS.

IMPROVEMENT IN HARVESTERS.

Specification forming part of Letters Patent No. 77,524, dated May 5, 1868.

To all whom it may concern:

Be it known that I, JO. RAMSEY, of Milford, in the county of Ellis and State of Texas, have invented certain new and useful Improvements on Reaping and Mowing Machines; and I do hereby declare that the following is a full, clear, and exact description thereof, reference being had to the accompanying drawings, making a part of this specification, in which—

Figure 1 is an elevation of one side of the improved machine. Fig. 2 is a longitudinal section through the machine, taken in the vertical plane indicated by line $x\ x$ in Fig. 3. Fig. 3 is a top view of the machine, with portion broken away. Fig. 4 is a bottom view of the driving-wheel for vibrating the lever which moves the sickle, showing the cam-head on said lever. Figs. 5 and 6 are views of my improved finger-guard.

Similar letters of reference indicate corresponding parts in the several figures.

This invention relates to certain novel improvements on that class of reaping and mowing machines in which the animals which move the machine are placed behind the cutting apparatus and the main frame.

The nature of my invention consists, first, in the manner herein shown of combining an endless wire, brace, or stay with two light disks or circular pieces of wood or metal, which have pins set in their periphery, for the purpose of making a strong light pin-wheel for operating the pitman-driver of a harvester, this construction being cheaper than the solid serpentine cam-wheel or solid pin-wheel, and answering all the purposes of the same, with less friction, it also being stronger and firmer than a wheel formed of two disks with cam-surfaces opposite one another, and serving to give a more regular motion; second, my invention consists, further, in constructing the guards in the manner herein shown and described, so that that part of the slot in which the sickle moves shall only be about the same size as the thickness of the sickle, while that part of the slot which is forward of the front ends of the sickle-sections shall be greatly enlarged in the form of a circle or ellipse. Thus, while I secure a perfect surface for the edges of the sickle to cut upon, I also prevent clogging by providing a free clearing-space in front of the ends of the sickle-sections.

To enable others skilled in the art to understand my invention, I will describe its construction and operation.

In the accompanying drawings, A A' represent the driving-wheels, which are both applied loosely upon the axle B; and a represents a forked clutch, which passes through the hub of the wheel A', so as to engage with lugs which are formed on a collar, a', that is keyed fast upon said axle. This clutch is used for engaging wheel A' with its axle B when it is desired to operate the sickle, and to disengage said wheel when it is not desired to operate the sickle.

C C represent two longitudinal beams, which project out in front and rear of the axle B, and are suspended beneath the same by means of the bearings b b, as shown. Beneath these beams C C, and secured to them by means of short posts, are two longitudinal beams, C' C', which extend forward of the axle B and beams C a sufficient distance to support the grain-platform D in front of the driving-wheels A A', and in front of the guard-board or fender D', which extends transversely across the lower beams in front of the drive-wheels.

The beams C C are connected together at their rear ends by means of a transverse bar, c, and at their front ends by means of a transverse bar, d. The ends of the two bars c and d project out laterally, and have the reel-supporting arms E E secured to them, as shown in Figs. 1, 2, and 3.

The front ends of the beams C' C' have the finger-beam e secured firmly to them, which beam has secured to it the guard-fingers g g, upon which the sickle g' reciprocates. One end of this sickle g' has a bent arm secured to it, to which arm a pitman-rod is attached, which plays in a groove in the finger-beam e, and is attached at its inner end to the forward end of a vibrating lever, G. This lever proceeds back, and has a cam-head, h, applied to its rear end, which is acted upon by means of studs i upon the peripheries of two wheels, J J, on the main axle B. The studs on wheels J are arranged at such distances apart and in such manner as to act alternately upon the tapering sides of cam h as the wheels, with their axle, are revolved, and to give a rapid vibrating motion to the lever G. The two wheels J J are keyed upon the axle B at suit-

able distances apart, and secured against lateral strain by means of the diagonal rods *j*, which pass around the studs *i*, and also strengthen these studs.

The tongue *K* has hounds *l l* secured to its forward end, which hounds are pivoted to the rear posts *3 3*, which connect the upper and lower beams of the main frame together at points 2 below the axle *B*. The tongue *K* proceeds back beneath the bar *c* a suitable distance, and is supported upon a flanged guide-wheel, *L*, the standard *L'* of which passes freely through the tongue, and has a handle secured upon its upper end, so that the driver, while sitting upon the seat *M*, can turn the wheel *L* either to the right or to the left, according to the direction required to move the machine.

To the cross-bar, at the front end of the tongue *K*, a lever, *N*, is connected by means of a link, *k*, which lever passes through an eye on bar, *c*, and proceeds back to a post, *n*, to which it is connected by a loop or staple, as shown in the drawings. The rear end of lever *N* is in a position where it can be grasped by the person sitting upon seat *M*, who can, by raising and lowering it, adjust the cutting apparatus higher or lower, as he may require.

In Figs. 5 and 6 I have represented enlarged views of a guard-finger which I employ in-

stead of guard-finger heretofore used. It is made of a rod of metal, bent in the form shown in Fig. 5, so as to leave an eye, *p*, which forms the front termination of the space in which the sickle works. This eye is tapered, as shown in Fig. 6, so as to afford as little obstruction as possible to its passage through the grass or grain. This eye *p* will allow the free escape of anything which may get into the space between the sickle and its guard.

Having described my invention, what I claim as new, and desire to secure by Letters Patent, is—

1. The pin-wheel *J J*, constructed of two light disks, with pins *i i* in their periphery, and with an endless bracing or staying wire, *j*, passed diagonally from one disk to the other around the pins *i i*, in combination with the device *G h*, which drives the sickle of a harvester such as described, all substantially as described.

2. The guard-fingers *g*, constructed, as shown in Figs. 5 and 6, with a narrow straight slot, terminating in an elliptical or circular eye, for the purpose set forth.

JO. RAMSEY.
